UNITED STATES PATENT OFFICE

WILLIAM SAYMON, OF BROOKLYN, NEW YORK

DESIGN FOR A LAMP RECEPTACLE

Application filed April 21, 1931. Serial No. 39,583. Term of patent 14 years.

To all whom it may concern:

Be it known that I, WILLIAM SAYMON, a citizen of the United States, residing in Brooklyn, county of Kings, and State of New York, have invented a new, original, and ornamental Design for Lamp Receptacle, of which the following is a specification, reference being had to the accompanying drawings, forming part thereof, in which,

Figure 1 is a view in elevation of a lamp receptacle showing one face thereof.

Figure 2 is a view similar to Figure 1 showing the opposite face thereof.

Figure 3 is a view in elevation showing the faces of the lamp receptacle which are disposed at right angles relatively to the faces illustrated in Figures 1 and 2, and

Figure 4 is a top plan view of the lamp receptacle.

I claim:

The ornamental design for a lamp receptacle, as shown.

WILLIAM SAYMON. [L. S.]
